UNITED STATES PATENT OFFICE.

RICHARD WEBB BURNETT, OF MONTREAL, QUEBEC, CANADA, ASSIGNOR TO HIMSELF, WILSON W. BUTLER, AND HENRY H. VAUGHAN, ALL OF MONTREAL, QUEBEC, CANADA.

GRAIN-DOOR LOCK.

1,133,534.

Specification of Letters Patent.

Patented Mar. 30, 1915.

Application filed November 11, 1912. Serial No. 730,661.

To all whom it may concern:

Be it known that I, RICHARD WEBB BURNETT, a resident of the city of Montreal, in the Province of Quebec, and Dominion of Canada, have invented certain new and useful Improvements in Grain-Door Locks; and I do hereby declare that the following is a full, clear, and exact description thereof.

My invention relates more particularly to the locks of removable grain doors and it has for its object to improve and simplify the means for retaining doors of this class.

It has been found that the door locks or retainers as heretofore constructed have frequently caused the doors to be jammed by the grain pressure and that they could only be opened with great difficulty or their destruction has been necessary to discharge the grain. My invention is designed to overcome this difficulty.

According to my invention the removable door is supported at opposite side edges against the pressure of the grain by fixed and displaceable door jambs, and the fixed jamb has a seat allowing the door limited movement to permit sufficient of the load to flow out of the car to relieve the pressure but by which the door is held until lifted from place by the crew unloading the car, the displaceable door jamb being adapted to be swung entirely out of the way. For full comprehension, however, of my invention reference must be had to the accompanying drawings forming a part of this specification in which similar reference characters indicate the same parts, and wherein:—

Figure 1 is a horizontal sectional view of a door-frame, grain-door and my improved door locking means; Fig. 2 is a transverse sectional view taken on line B B Fig. 1; Fig. 3 is an interior elevation of the portion of the car contiguous to and including the door frame; and Fig. 4 is a transverse vertical sectional view taken on line C C Fig. 2.

My improved grain door retaining and locking means can be applied to any type of car having vertical discharging doors of which the door posts are indicated at b, b'.

One of the door posts has a vertical groove c in line with which a socket d is set in the threshold e. A round hinge bar is divided longitudinally and diametrically and the halves f f thereof are secured preferably by rivets g to the opposite sides of

the wider leg of an unequal angle-iron h thus forming with the portion of the angle iron between them a substantially round hinge bar. The lower ends of these half-round parts protrude downwardly below the angle iron and are rotatably seated in the socket d, and a hinged relation between the hinge bar and door post is effected by a pair of straps h¹, h² secured to the door post and clasping the hinge bar, the straps h² passing through a slot h³ in the angle iron h. The door post is notched at its outer edge as at m to receive the angle iron h as will be presently shown, the post extending in width sufficiently from the groove toward the interior of the car to equal the width of the angle-iron outside measurement while the width from the groove to the outside notched edge equals the width of the angle iron inside measurement. The removable grain door is indicated at i. This angle iron serves the double purpose of a door jamb and lock and the connection between the hinge bar f and door post and between the angle iron and grain door presents an effective grain seal.

The door is held against inward displacement relative to the car at one side by a strap k extending from top to bottom of the grain door and having openings k' therein through which the removable grain doors may be nailed to the door post when necessary, this strap being bent to substantially bayonet form in cross-section and supported by a filling strip k². The opposite side edge of the door is supported by pivoted clips p held in place by a strap r and lag screws s, a strap being, like the strap k', bent to substantially bayonet form in cross section and supported by a filling strip t. These straps k and r besides serving directly and indirectly respectively as supports for the door protect the edges of the latter from the plow or cable pulling the latter when the car is being discharged thereby and they also prevent the side posts b' of the door frame from being destroyed by having nails driven into the same at many different places, when removable doors are to be nailed in place, the nailing being limited to the space exposed by the openings k'.

The angle-iron h is located in positions retaining the door and thrown clear of the door by two or more pairs of buttons u v, the buttons of each pair being adapted when

the angle iron is in its respective positions to engage a slot *w* in the latter and when turned prevent displacement of the angle-iron.

- 5 The strap *h* is spaced from the door post *b* a sufficient distance to allow limited movement of the door outwardly.

Another advantage of the straps *h* *h*² is that they serve to protect the door posts 10 against damage from trucks used for loading the car with other lading than wheat such as bagged material, machinery and other things; and another advantage of the 15 grooved door post is that it braces the hinge bar *f f* and prevents distortion thereof.

Operation: The angle-iron is swung to door locking position and the buttons *u u* turned to lock it in place. The clips *p* are 20 swung to clear the door and the door is set with one edge in the seat presented by the strap *h*, filler *h*² and door post *b*' then swung 25 into contact with the angle-iron *h* after which the clips *p* are moved into engagement with the door. When it is desired to discharge the car the buttons *u* are turned to register with the slots *w* which will release 30 the angle-iron and allow it to swing with its hinged bar *f* to the dotted position shown in Fig. 1, the pressure of the grain within the car forcing the door to the dotted position shown, thus permitting some of the lading 35 to flow out. When the pressure upon the door has in this manner dropped sufficiently the train crew can lift the door from place and allow the discharge of the lading to be completed.

What I claim is as follows:—

1. The combination with the side of a car 40 having an opening and a door adapted to swing outwardly through the opening, of a

door jamb of angle cross-section and means pivotally securing the edge of the flange of the door jamb to one side of the door-opening midway between the inside and outside faces of the car side and in position to lie 45 with one flange in flat contact with the said side of the door opening and its other flange in the plane of and sustaining the door when closed and when swung out to clasp the outside edge of the said side of the door-opening. 50

2. The combination with the posts of a door opening in the side of a car and a door, of a combined door jamb and lock consisting of an angle-iron, the said angle-iron being constructed and arranged when in door retaining position to have one flange lie in flat contact with one of the door posts and the other flange lie in the plane of and sustain the door when closed, a hinge bar carrying the angle-iron and consisting of a pair of members riveted to opposite sides of the flange of the angle-iron and means pivoting the hinge bar in the door frame. 55

3. The combination with the side of a car 60 having an opening therein and a door for closing the said opening, of a swinging door retaining device of angle cross-section, means securing the retaining device at one side of the door opening, such retaining device being constructed and arranged to clasp the outside edge of the said side of the opening when out of door retaining position. 70

In testimony whereof I have signed my name to this specification in the presence of 75 two witnesses.

RICHARD WEBB BURNETT.
